UNITARY DOORFRAME TRIMMING DEVICE

Rose S. Ferrara, Bronx, N. Y.

Application November 30, 1951, Serial No. 259,118

6 Claims. (Cl. 160—83)

1

This invention relates to devices for trimming or decorating upper portions of doorframes to produce a pleasing effect and environment within a room or compartment controlled by the door of such room. More particularly, the invention deals with a device of this type and kind which is unitary in construction, so as to facilitate simple merchandising and packaging of the device, as well as simple installation thereof.

The novel features of the invention will be best understood from the following description, when taken together with the accompanying drawing, in which certain embodiments of the invention are disclosed and, in which, the separate parts are designated by suitable reference characters in each of the views and, in which:

Fig. 1 is a perspective view, illustrating a doorframe with one of my improved devices mounted thereon.

Fig. 2 is a diagrammatic side view of a part of the frame showing the device mounted in position thereon; and

Fig. 3 is a plan and sectional view of the device in collapsed or folded position for packaging or shipment.

In Fig. 1 of the drawing, I have indicated at 10 a doorframe comprising side frame strips 11 and 12 and an upper cross-strip 13 and, at 14, I have shown a door hinged to the strip 11 to swing outwardly with respect to a room or compartment, access to which is controlled by the door 14. In other words, the perspective view is visualized from the interior of a room or compartment.

At 15 I have shown one of my improved unitary devices to trim, characterize or ornament the upper portion of the doorframe 10. The device 15 comprises an elongated strip 16, which may be termed a bar, rod or frame member, preferably made of light material and of any desired cross-sectional contour. For example, a plastic strip or bar could be employed and this bar is disposed in a hemmed portion 17 of a fabric or plastic sheet 18, the hem being disposed adjacent one side edge portion 19 of the sheet, the edge of which is preferably scalloped or otherwise ornamented, as indicated at 20.

The flange portion 19 is formed by using a facing sheet 19' suitably secured to 19 and 19' includes a portion 17', which forms part of the hem 17, as clearly illustrated in Fig. 2 of the drawing. The other or upper edge 21 of the sheet 18 has a portion 22 turned upon itself and passed through these portions 21 and 22 at spaced intervals are eyelets, or the like 23, to

2

engage suitable fastening devices such, for example, as hooks 24 which are fixed to the upper portion of the strip 13 of the doorframe.

The bar or rod 16 extends beyond the ends of 5 the sheet 18 to form forked pivot or hinge portions 16', note Fig. 3, with which bent or curved ends 25 of brace rods, strips or frame members 26 are hingedly coupled, as clearly seen in Fig. 3, the rods or strips 26 having bracket ends 27 through which a screw or other fastening device 28 can be passed in securing the bracket ends 27 to the side strips 11 and 12 of the doorframe, as illustrated in Figs. 1 and 2 of the drawing.

With the construction shown, it will be apparent that the entire strip 18, including the edges 19, 21, can be rolled around the bar or rod 16 in the manner diagrammatically shown in Fig. 3, and the bars 26 folded thereon to form an elongated compact package, which will facilitate packaging and shipment thereof.

At the same time, it will be understood that, when the purchaser wishes to install the device, all that is necessary is to extend the rods 26 to a position at right angles to the rod 16 and then unwind 20 the strip 18. Then the fastening or coupling devices 24 are positioned on the doorframe strip 13, the eyelets being suitable for marking the position of the devices 24 on the strip 13, after which the eyelets are coupled with the devices 24; then the two rods 26 are moved to a position 25 on the strips 11 and 12, so as to produce the desired or required inclination of the sheet 18 or extension of the device into the room, after which the screws or other fastenings 28 are 30 employed to secure the brackets 27 to the strips 11 and 12.

It will be understood, in this connection, that the fastening devices 28 are not absolutely essential, as the brackets 27 may simply rest against the strips 11 and 12, without the need of any additional support. Here, it will be desirable that the hinge coupling between 26 and 16, or 16', will be a frictional hinge, so as to obviate free relative movement between the parts.

It will be understood that devices of the character described can be produced in any desired decorative material to produce the desired decorative effect over the door opening consistent with the curtains, draperies and the like employed in the room, in which the device is to be used. The particular shape and contour of the sheeting may also be modified to suit different uses and installations. The entire purpose of my invention resides in providing over a doorframe, which is usually blank and unattractive,

a device which will produce a more pleasing and decorative effect consistent with the room in which the door opening is arranged. In the home, devices of this type and kind can be employed in kitchens, dining rooms, living rooms and the like; whereas, in public establishments, such as clubs, restaurants, hotels and the like similar ornamentation and decorative environments can be created.

Having fully described my invention, what I claim as new and desire to secure by Letters Patent is:

1. A doorframe trimming device, comprising a flexible sheet having an upper reinforced attaching edge, an elongated rod fixed to the lower portion of said sheet, said rod having ends terminating at side portions of the sheet, a pair of brace rods pivotally coupled to the ends of said first named rod, said sheet being adapted to be normally rolled upon the first named rod to assume a compact mounting thereon, and said brace rods being collapsible onto the rolled sheet and assuming a position parallel with respect to the first named rod when the device is in collapsed position.

2. A doorframe trimming device, comprising a flexible sheet having an upper reinforced attaching edge, an elongated rod fixed to the lower portion of said sheet, said rod having ends terminating at side portions of the sheet, a pair of brace rods pivotally coupled to the ends of said first named rod, said sheet being adapted to be normally rolled upon the first named rod to assume a compact mounting thereon, said brace rods being collapsible onto the rolled sheet and assuming a position parallel with respect to the first named rod when the device is in collapsed position, free ends of said brace rods having enlarged brackets, and the brace rods joining the first named rod in curved portions.

3. A doorframe trimming device, comprising a flexible sheet having an upper reinforced attaching edge, an elongated rod fixed to the lower portion of said sheet, said rod having ends terminating at side portions of the sheet, a pair of brace rods pivotally coupled to the ends of said first named rod, said sheet being adapted to be normally rolled upon the first named rod to assume a compact mounting thereon, said brace rods being collapsible onto the rolled sheet and assuming a position parallel with respect to the first named rod when the device is in collapsed position, free ends of said brace rods having enlarged brackets, the brace rods joining the first named rod in curved portions, and the sheet including a projection flap portion extending beyond said rod.

4. A doorframe trimming device, comprising a flexible sheet having an upper reinforced attaching edge, an elongated rod fixed to the lower

portion of said sheet, said rod having ends terminating at side portions of the sheet, a pair of brace rods pivotally coupled to the ends of said first named rod, said sheet being adapted to be normally rolled upon the first named rod to assume a compact mounting thereon, said brace rods being collapsible onto the rolled sheet and assuming a position parallel with respect to the first named rod when the device is in collapsed position, free ends of said brace rods having enlarged brackets, the brace rods joining the first named rod in curved portions, the sheet including a projecting flap portion extending beyond said rod, an inner facing for the flap portion, and said facing having a part engaging said first named rod.

5. A doorframe trimming device, comprising a unitary structure, normally assuming an elongated compact package and adapted to be extended to form a decorative finish at the upper portion of a doorframe, said device, when extended, comprising a sheet of flexible material having a reinforced upper edge, including means for attachment to the upper cross-rail of a doorframe, the lower edge portion of the sheet having a transverse member fixed thereto and extending at side edges of said sheet, a pair of brace members pivotally coupled to the ends of the first member, and said brace members having bracket ends adapted to bear upon side members of a doorframe in support of the device on the doorframe.

6. A doorframe trimming device, comprising a unitary structure, normally assuming an elongated compact package and adapted to be extended to form a decorative finish at the upper portion of a doorframe, said device, when extended, comprising a sheet of flexible material having a reinforced upper edge, including means for attachment to the upper cross-rail of a doorframe, the lower edge portion of the sheet having a transverse member fixed thereto and extending at side edges of said sheet, a pair of brace members pivotally coupled to the ends of the first member, said brace members having bracket ends adapted to bear upon side members of a doorframe in support of the device on the doorframe, and said sheet having a flap portion extending beyond the first named member.
